DUST BAG HOLDER FOR A SUCTION CLEANER

Paul Emile Gaudry, Montreal, Canada, assignor to Aktiebolaget Electrolux, Stockholm, Sweden, a corporation of Sweden

Application April 1, 1958, Serial No. 50,286

Term of patent 14 years

(Cl. D9—2)

FIG. 1

FIG. 2

FIG. 4

Fig. 1 is a side elevational view of a dust bag holder for a suction cleaner showing my new design;

Fig. 2 is a top plan view thereof;

Fig. 3 is an elevational view thereof as seen from the left-hand end of Fig. 2; and

Fig. 4 is an elevational view thereof as seen from the righthand end of Fig. 2.

The bottom and side of the dust bag holder not shown are the same in appearance as the top and side shown.
I claim:

The ornamental design for a dust bag holder for a suction cleaner, as shown.
